METHOD OF PREVENTING ELECTRIC CHARGING OF LIQUID HYDROCARBONS

Hideo Marumo, Morio Ninomiya, and Yasushi Matsuzaki, Tokyo, and Makoto Takai, Chiba, Japan, assignors to Lion Yushi Kabushiki Kaisha
 No Drawing. Filed Feb. 1, 1965, Ser. No. 429,628
 6 Claims. (Cl. 44—63)

The present invention relates to a method of preventing the accumulation of an electric charge by liquid hydrocarbons; to liquid hydrocarbons treated by this method, or more specifically to a method of preventing the accumulation of an electric charge by liquid hydrocarbons such as various kinds of petroleum fuel, dry-cleaning benzene, paint thinner, etc., by adding thereto some metallic salt of a non-alkaline metal selected from among amphoteric surface active agents having the following formulas:

(where R denotes a hydrocarbon group with 8 to 22 carbon atoms; R' is hydrogen or a lower alkyl group; A is oxygen or an imino group; M is a nonalkaline metal (i.e., a metal other than those in Group I of the long form of the periodic table of the elements); m, n are integers; and x, y are integers dependent on the valence of the nonalkaline metal and such as to bring the bracketed group and the metal into stoichiometric proportion); and to liquid hydrocarbons to which some metallic salt of a nonalkaline metal selected from among the above-mentioned amphoteric surface active agents has been added.

The demand for petroleum and organic solvents has been on the increase in recent years. Meanwhile, a substantial part of the accidental fires and explosions thereof are presumably attributed to the discharge of static electricity. Petroleum and organic solvents accumulate an electric charge during transportation through a pipe-line, through agitation in tanks, or due to vibration while in transit in tank cars or the like. This is believed to result when the inner one of the double layers of electric charge formed near the vessel wall moves relative to the other, and it is a well-known fact that the more violent the movement of the liquid, the greater the electric charge. Such accidents, therefore, may be prevented by eliminating such violent conditions as contribute to the accumulation of an electric charge, by avoiding the formation of an explosive gas mixture, or by assuring perfect grounding of the vessel. But petroleum fractions and some types of organic solvents have extremely low electric conductivity. For instance, gasoline and kerosene have a specific conductivity as low as 0.3 to 50 picomho/m. ($10^{-12}/\text{ohm}^{-1}/\text{m.}$); and the accumulated charge in such liquids may easily reach the critical limit at which it will discharge instead of leaking off. A most effective way of facilitating leakage of the charge built up in such liquids is to increase their electric conductivity. For instance, A. Klinkenberg has re-

ported that gasoline or kerosene, with its specific conductivity enhanced to 50-500 picomho/m., would be safe to a certain extent, and if the value were further raised to over 1,000 picomho/m., it would be safe enough under 5 severe conditions (A. Klinkenberg and J. L. Van der Minne, "Electrostatics in the Petroleum Industry").

The present inventors have discovered that if a metallic salt of a nonalkaline metal selected from among the amphoteric surface active agents with the above-mentioned general Formulas I to IV is added in the amount of 1 to 100 p.p.m. (from 1 to 100 kg. per 1000 m.³) to such liquid hydrocarbons as various kinds of petroleum fuel, dry-cleaning benzene, paint thinner, etc., the electric conductivity of these liquids will be remarkably improved 15 and the charge density of such liquids will be much lower than that of untreated liquids. The larger the proportion of added compounds to liquid hydrocarbons, the higher the electrical conductivity of these liquids will become. When, however, too much of said compounds is added, they will 20 affect the dispersing agent in the paint when said liquids are applied to paint, thereby causing sedimentation of the paint, and when applied to gasoline, will cause the deposit of solids on the cylinder. To prevent such troubles, the inventors have investigated the appropriate proportion 25 of said compounds to liquid hydrocarbons and reached the conclusion that 1 to 100 p.p.m. will assure sufficient electric conductivity without adversely affecting the essential properties of said liquids. Particularly, when the addition exceeds 10 p.p.m., the electric conductivity will increase to over 1000 picomho/m., while less than 50 p.p.m. will never affect the essential properties of the liquids. Consequently, the optimum addition range is from 10 to 50 p.p.m. Unlike many other compounds in the prior art, when liquid hydrocarbons to which said compounds have 30 been added are transported together with water in a pipeline, said compounds will not be extracted by the water, nor will they be emulsified and dispersed. Moreover, they contain very little sediment. For example, if gasoline to which said compounds have been added is employed, there 35 will occur no resulting deposit on the cylinders and there will be no unfavorable effect on the essential properties of said gasoline. These are the advantages of the present invention.

In the metallic salt of a nonalkaline metal selected 45 from among the above-mentioned amphoteric surface active agents with general Formulas I to IV, R is usually a hydrocarbon and is most easily synthesized with an excellent effect of electric charge prevention, when the number of carbon atoms ranges from 8 to 22; but even with the 50 carbon atoms less than 8 or more than 22, a certain electric charge preventing effect is observable. R' is hydrogen or a lower alkyl group, for example, a methyl group. A is oxygen or an imino group; and m, n are integers. Most desirably, m in the general Formulas I and II should be 55 from 1 to 20, while the sum of m and n in IV should be 2 to 20. However, even at the value of over 20, the electric charge preventing effect exists. For instance, first ethylene oxide and then propylene oxide may be added to (CHR'CHR'A)_m. M can be any nonalkaline metal, i.e. 60 any metal not falling within group I in the long form of the periodic table of the elements; specifically, it can be magnesium, calcium, barium, lanthanum, chromium, molybdenum, manganese, iron, cobalt, nickel, copper, silver, gold, zinc, cadmium, mercury, aluminum, tin, lead or arsenic. Of these, the best are magnesium, calcium, barium, zinc, aluminum and lead, but others are also effective 65 for preventing the accumulation of an electric charge. x, y are numbers dependent on the valence of the metal. Of course, the compound may be a mixture of two or more 70 of the above-mentioned metallic salts. The compounds with the general Formulas I to IV can be synthesized as follows:

(1) The compounds with the general Formula I can be obtained by reacting polyamines such as ethylene diamine, diethylene triamine, or aminoethyl ethanolamine with a high molecular weight fatty or its esters or chlorides to produce amides, and reacting these amides as such or the reaction products of said amides and ethylene oxide, propylene oxide, or ethylene imine, with sodium-monochloride acetate to produce a sodium salt, and then effecting a double decomposition of the sodium salt with an inorganic salt of the nonalkaline metal. The following is an example of this process:

In the foregoing and in the ensuing formulae R represents a hydrocarbon group with 8 to 22 carbon atoms.

(2) The compounds having the general Formula II can be obtained by reacting polyamines like ethylene diamine, diethylene triamine or aminoethyl ethanolamine with a high molecular weight fatty acid or its esters or chlorides, to produce imidazol derivatives as they are (or the product obtained by reacting said imidazol derivatives with ethylene oxide, propylene oxide or ethyleneimine) with sodium-monochloride acetate to produce a sodium salt, and then effecting a double decomposition of said sodium salt with an inorganic salt of the nonalkaline metal.

The following is an example of this process:

(3) The compounds with the general Formula III can be obtained by hydrolyzing the reaction products of a high molecular weight alkylamine and an acrylic ester, or a methacrylic ester of acrylonitrile with caustic soda, to produce a sodium salt, and then effecting a double decomposition of said sodium salt with an inorganic salt of the nonalkaline metal. The following is an example of this process:

(4) The compounds having the general Formula IV can be obtained by reacting a high class alkylamine with ethylene oxide, propylene oxide or ethyleneimine, and reacting the product of this reaction with sodiummonochloride acetate to produce a sodium salt and then effecting a double decomposition of said sodium salt with an inorganic salt of a nonalkaline metal. The following is an example of this process:

(m+n=2)

The liquid hydrocarbons, to which the proposed addition can be profitably made, have a boiling point in the range of about 30 to 300° C. and include gasoline, kerosene, light oil, benzene, toluene, xylene, chlorobenzene, nitrobenzene, bromobenzene, hexane, heptane, dimethyl-ether, diethylether, dioxane, turpentine oil, carbon disulfide and similar substances; and even low boiling point liquefied gases such as liquefied propane and liquefied butane.

In the following, actual examples of executing the invented method are cited with the electric charge preventing effect illustrated by the measurements of electric conductivity and charge density when inflammable liquids are treated with non-alkaline metal salts which are amphoteric surface active agents.

(1) The electrical conductivity was measured by means of an insulating oil testing electrode (TR-44 manufactured by Takeda Rikenkogyo K.K.); and the volume resistivity under a one minute application of 100 v. was measured by means of a Vibrating Reed Electrometer (TR-84B manufactured by Takeda Rikenkogyo K.K.).

(2) The charge density was measured by a set-up consisting of a grounded stainless steel tank (1000 ml.), a stainless steel pipe (inner diameter 3 mm., length 50 cm.), a stopper, a Faraday cage and a Vibrating Reed Electrometer. First, 500 ml. of a sample liquid was poured into the tank, and after its flow rate had been adjusted by the stopper to 100 ml./min., was drained down the pipe to be received by the Faraday cage, where the magnitude of charge was measured.

Example 1

Metal salts of N-carboxymethyl-N-hydroxyethyl-N'-undecyloyl-ethylenediamine having the following structural formula falling within the scope of general Formula I:

were added respectively to gasoline, jet fuel, kerosene, light oil, benzol, toluol, and xylol (all produced by Mitsubishi Petroleum). The measured values of electric conductivity and charge density are cited below.

TABLE 1.—ELECTRIC CONDUCTIVITY AND CHARGE DENSITY OF LIQUIDS TO WHICH COMPOUNDS WITH THE STRUCTURAL FORMULA V HAVE BEEN ADDED

M	Inflammable organic liquid	Electric conductivity (picomho/m.)				Charge density (microcoulomb/m. ³)

	Toluol	3.4	570	1,950	2,800	48.8	25.7	15.0	6.1

As seen from Table 11, the inflammable organic liquids which have been treated with compounds with the Formula XV have a considerably higher electric conductivity and a lower charge density than untreated ones.

Example 12

Metal salts of bis (polyoxypolyethylene)-octadecyl-carboxymethyl-ammonium hydroxide having the following structural formula within the scope of general Formula IV:

were added respectively to gasoline, jet fuel, kerosene, light oil, benzol, toluol and xylool (all produced by Mitsubishi Petroleum). The measured volumes of electric conductivity and charge density are given below.

What is claimed is:

1. An inflammable organic liquid hydrocarbon composition having antistatic properties comprising an inflammable organic liquid hydrocarbon and effective antistatic amounts of at least one metallic salt of a nonalkaline metal which is an amphoteric surface active agent with respect to said liquid and is selected from the group consisting of:

TABLE 12.—ELECTRIC CONDUCTIVITY AND CHARGE DENSITY OF LIQUIDS TO WHICH COMPOUNDS HAVING THE FORMULA XVI HAVE BEEN ADDED

	Xylool	3.8	800	2,050	3,170	50.5	27.4	16.0	5.2

As seen from Table 12, the inflammable organic liquids which have been treated with compounds having the

where R is a hydrocarbon group with 8 to 20 carbon atoms; R' is selected from the group consisting of hydro-

gen and a lower alkyl; A is selected from the group consisting of oxygen and an imino; M is a nonalkaline metal; m and n are integers; and x and y are integers dependent on the valence of the nonalkaline metal which bring the bracketed group and the metal into stoichiometric proportion.

2. The composition of claim 1 wherein the amount of said amphoteric surface active agent present in said composition is from 1 to 100 p.p.m.

3. The inflammable organic liquid hydrocarbon composition of claim 1 comprising from 10 to 50 p.p.m. of said metallic salt of a nonalkaline metal.

4. The inflammable organic liquid hydrocarbon composition of claim 1 in which at least one of said metallic salts of a nonalkaline metal has the formula

where R is a hydrocarbon with 8 to 22 carbon atoms; R' is selected from the group consisting of hydrogen and a lower alkyl; A is selected from the group consisting of oxygen and an imino group; M is a nonalkaline metal; m is an integer; and x , y are integers dependent on the valence of the nonalkaline metal.

5. The inflammable organic liquid hydrocarbon composition of claim 1 in which at least one of said metallic salts of a nonalkaline metal has the formula
